UNITED STATES PATENT OFFICE.

JOHN TAYLOR, OF CHICAGO, ILLINOIS.

AUTOMATIC TOILET-LOCK.

1,292,146.

Specification of Letters Patent. Patented Jan. 21, 1919.

Application filed July 26, 1917. Serial No. 182,832.

To all whom it may concern:

Be it known that I, JOHN TAYLOR, a citizen of the United States, residing at Chicago, in the county of Cook and State of Illinois, have invented certain new and useful Improvements in Automatic Toilet-Locks, of which the following is a specification.

The invention is particularly adapted to 10 the toilets of railway cars, and has for its object the provision of means whereby to control the dumping of the pan.

A troublesome problem in connection with the operation of railway trains has to do 15 with the prevention of the dumping and flushing of the toilet while the train is standing at the station in towns along the line, and the situation is aggravated where the Pullmans for late night trains are made up 20 and allowed to stand at terminals for several hours before the leaving time of the train, for the convenience of passengers who may wish to retire.

According to the present invention, the 25 toilet facilities are available for the use of passengers at all times, but the flushing of the toilet and the dumping of the contents to the ground is automatically restricted to such time as the train is moving at a predetermined rate of speed calculated to be that 30 at which the train will have left the station and town.

I accomplish this result by providing dump pans in duplicate, the upper being 35 at all times under the control of a manually operated handle while the lower pan, which controls the outlet from the bowl, can be operated only when the car is running. The interspace between the dump pans provides 40 for the retention and accumulation of matter dumped from the upper pan. I furthermore preferably make provision for the automatic control of the lower auxiliary dump pan by the utilization of the electric current supplied from the axle driven generator of the present system of car lighting and heating to effectuate an electro-magnetic connection between the lower dump pan and the operating handle when a predetermined 45 speed of the train produces a predetermined generator output sufficient to energize the magnetic connection. I also provide means, utilizing the storage batteries of the lighting system, whereby the train porter is enabled 50 to couple the two pans and effect the flushing of the toilet in case of failure of

the generator or where other emergency may arise.

In order that the invention and the manner of its operation may be readily understood, a preferred embodiment of the same is set forth in the accompanying drawing and in the following detailed description based thereon. Obviously many modifications of the particular operating and controlling 60 means may be employed without departure from the spirit and essence of the invention as set forth in the appended claims, wherefore it is to be understood that the drawing and description are to be taken in an illustrative and not in an unnecessarily limiting 65 sense. In the drawing—

Figure 1 is a view of a toilet embodying this invention, shown partially in side elevation and partially in vertical section; 70

Fig. 2 is a similar view taken at right angles to Fig. 1;

Fig. 3 is an enlarged detail vertical section through the electro-magnetic coupling means; 80

Fig. 4 is a similar view showing the parts in uncoupled relation; and

Fig. 5 is a diagram illustrating the electric connection.

Having reference to Figs. 1 and 2 of the 85 drawing, the bowl of the toilet is indicated at 11 provided with a seat 12 and a cover 13. The interior of the bowl is divided by the wall 14 in two compartments, an upper one 15 and a lower one 16. The outlet from 90 the upper compartment is controlled by the usual dump pan 17 having projecting therefrom a lever arm 18 connected by means of a link 19 to a second lever 20, to one arm of which is connected the operating rod 21. 95

The outlet from the lower compartment 16 is controlled by a second dump pan 22 similarly pivoted at 23 and provided with a projecting lever arm 24. The lever arm 18 has pivoted thereto at 25 a coupling 100 member 26 to slide telescopically within the coupling member 27 which is pivoted to the lever arm 24 at 28. A permanent connection or coupling between the members 26 and 27 may be effected by means of the set 105 screw 29 threaded in the boss 30 formed on the coupling member 27 and arranged to engage with its inner end 31 within a notch 32.

In order to provide for coupling and uncoupling the members 26 and 27 in the normal operation of the device, a box 33 is mounted upon the coupling member 27 and

upon the wall of this box at 34 is pivoted a
 5 detent 35 the nose 36 of which is arranged to
 project through an opening in the coupling
 member 27 and to engage within a notch 37
 of the coupling member 26. A leaf spring
 10 38 attached to the detent 35 and bearing with
 its lower end against the wall of the box or
 the member 27 serves to lightly hold the
 detent in engaging position as illustrated in
 15 Fig. 3. However, the rounded engagement
 of the nose of the detent with the notch of
 the coupling member 26 is such that the ten-
 sion of the spring 38 is not of itself suffi-
 20 cient to hold the two in engagement but the
 upward movement of the coupling member
 26 will ordinarily expel the nose 36 of the
 detent from the notch. A link 39 is pivoted
 25 at 40 to the detent at one side of its pivot
 point 34, the lower end of the link 39 over-
 lying the armature 41 of the magnet 42,
 which armature is pivoted at 43 to the wall
 30 of the box. The magnet 42 is supplied
 from the axle driven generator of the usual
 car lighting system, diagrammatically illus-
 trated at 44 in Fig. 4, said system including
 35 the usual automatic switch indicated at 45
 and the hand switch indicated at 46; and
 also including the storage batteries 47 for
 supplying the lamps 48 when the car is at
 40 a stand still or running at a slow speed.

Assuming the hand switch to be in its nor-
 45 mal position connecting the terminals 47 and
 48 on the one hand and the terminals 49 and
 50 on the other, the magnet 42 is not ener-
 gized and the detent 36 is not held in posi-
 55 tion to couple the members 26 and 27 until
 sufficient current is generated by the incre-
 ment of speed to close the automatic switch
 45. Under such conditions, the car being at
 60 rest or running at a speed below, say fifteen
 miles per hour, the lower dump pan 22 is not
 coupled with the upper dump pan 17 and if
 the upper compartment 15 be flushed by
 65 the dumping of the pan 17 the contents of
 the compartment 15 will be deposited in the
 lower compartment 16 upon the pan 22, the
 coupling members 26 and 27 sliding loosely
 70 one within the other. If, however, the car
 reaches a speed of, say fifteen miles per hour,
 75 the output of the generator 44 will be suffi-
 cient to close the automatic switch 45 caus-
 ing the current to flow through the magnet
 80 42, and back to the generator, energizing the
 magnet 42 and lifting its armature 41 and,
 85 by means of the link 37 forcing the nose 36
 of the detent 35 into the notch 29 thereby
 effectually coupling the members 26 and 27
 together. If now, the operating rod or han-
 90 dle 21 be lifted both the upper dump pan 17
 and the lower dump pan 22 will be tilted,
 the members 26 and 27 forming for the time
 being a rigid connection between the two
 95 operating lever arms 18 and 24.

It will thus be seen that the coupling of
 100 the members 26 and 27 is entirely automatic

and takes place only when the car has at-
 tained a speed of a predetermined number
 of miles per hour.

For emergency use, in case of failure of
 the generator, or the arising of other condi-
 10 tions making it desirable to dump the matter
 accumulated within the compartment 16, the
 train porter may throw the switch 46 to the
 opposite side so as to connect the terminal 48
 15 with the terminal 51 and the terminal 50
 with the terminal 52. The magnet 42 is
 thereby brought into circuit with the storage
 batteries 47, whereby it is energized and the
 20 detent 35 is caused to couple the members 26
 and 27, whether the train be running at the
 25 predetermined speed or no.

I claim:

1. In a toilet for railway cars, the combi-
 30 nation with a bowl, the dump pan, and the
 handle for operating the same, of an aux-
 iliary pan, and electro-magnetic couplings
 35 between the two pans, a source of current
 supplied to the magnet, and means to control
 the flow of current whereby to connect and
 disconnect the pans and enable the upper
 40 pan to be operated jointly with or inde-
 pently of the lower pan.

2. In a toilet for railway cars, the combi-
 45 nation with a bowl, the dump pan, and the
 handle for operating the same, of an aux-
 iliary pan below the first pan, an electro-
 50 magnetic coupling device between the two
 pans, a source of current to the magnet, and
 means to automatically control the flow of
 55 current whereby to connect and disconnect
 the pans and enable the upper pan to be
 operated jointly with or independently of
 the lower pan.

3. In a toilet for railway cars, the combi-
 60 nation with a bowl, the dump pan, and the
 handle for operating the same, of a second
 pan disposed below the first pan and con-
 trolling the outlet from the bowl, a loose
 65 connection between the two pans, electro-
 magnetic means for coupling the parts of
 the loose connection to form a fast connec-
 70 tion, whereby the upper pan may be oper-
 ated jointly with or independently of the
 lower pan.

4. In a toilet for railway cars, the combi-
 75 nation with a bowl, the dump pan, and the
 handle for operating the same, of a second
 pan disposed below the first pan and con-
 trolling the outlet from the bowl, a loose
 80 connection between the two pans, electro-
 magnetic means for coupling the parts of
 the loose connection to form a fast connec-
 85 tion, whereby the upper pan may be oper-
 ated jointly with or independently of the
 lower pan, said operating means comprising
 90 an electro-magnet, and an axle driven gen-
 erator supplying the magnet, whereby the
 coupling of the two pans will be automati-
 95 cally effectuated as the speed of the train
 rises above a predetermined minimum.

5. In a toilet for railway cars, the combination with a bowl, the dump pan, and the handle for operating the same, of a second pan disposed below the first pan and controlling the outlet from the bowl, a loose connection between the two pans, a detent for coupling the connection between the pans, an electro-magnetic device for operating said detent, said operating means comprising an electro-magnet acting on the detent, and an axle driven generator supplying the magnet, whereby the two pans will be coupled and uncoupled automatically as the speed of the train rises above or falls below a predetermined rate.

6. In a toilet for railway cars, the combination with a bowl, a pivoted dump pan therein, an operating lever extending from the pan to the exterior of the bowl, of a second pan similarly mounted below the first pan and controlling the outlet to the bowl, an operating lever extending from the second pan, telescopic coupling members one carried by each lever and arranged to slide freely, a detent arranged to connect the two telescopic members, an electro-magnet, a connection between the magnet armature and the detent whereby as the armature is attracted by the magnet the detent will be caused to couple the said members, and an axle driven generator supplying the magnet, whereby the two pans will be coupled and uncoupled automatically as the speed of the train rises above or falls below a predetermined rate.

7. In a toilet for railway cars, the combination with a bowl, a dump pan, and the handle for operating the same, of an auxiliary pan below the first pan, electro-magnetic coupling means between the two pans, an axle driven generator for supplying the electro-magnetic means, whereby the two pans will be coupled and uncoupled automatically as the speed of the train rises above or falls below a predetermined rate, and emergency means for effecting such coupling comprising storage batteries in circuit with the electro-magnetic means, and a switch in said circuit whereby in case of emergency the magnet may be energized to couple the pans independently of the train speed.

8. In a toilet for railway cars, the combination with a bowl, a pivoted dump pan therein, an operating lever extending from the pan to the exterior of the bowl, of a second pan similarly mounted below the first pan and controlling the outlet to the bowl, an operating lever extending from the second pan, telescopic coupling members one carried by each lever and arranged to slide

freely, a detent arranged to connect the two telescopic members, an electro-magnet, a connection between the magnet armature and the detent whereby as the armature is attracted by the magnet the detent will be caused to couple the said members, and an axle driven generator supplying the magnet, whereby the two pans will be coupled and uncoupled automatically as the speed of the train rises above or falls below a predetermined rate, and emergency means for effecting such coupling comprising storage batteries in circuit with the magnet, and a switch in said circuit, whereby in case of emergency the magnet may be energized to couple the pans independently of the train speed.

9. In a toilet for railway cars, the combination with the bowl, a pan controlling the outlet from the bowl, and manually operable normally uncoupled means to dump said pan, of means controlled by the train-speed to automatically couple the operating means whereby to enable the toilet to be flushed only when the train-speed reaches a predetermined minimum.

10. In a toilet for railway cars, the combination with the bowl, an axle driven electric generator, and means controlled by the generator output enabling the flushing of the bowl only when the train speed exceeds a predetermined minimum.

11. In a toilet for railway cars, the combination with the bowl, and manually operable means for flushing the same, of an electric generator having a variable output dependent upon train speed, and means energized by said generator for rendering the manually operable means effective only when the generator output exceeds a predetermined voltage.

12. In a toilet for railway cars, the combination with the bowl, the dump pan, and the operating handle therefor, of an auxiliary pan, and means to automatically couple the two pans together for joint operation when the train speed rises above a predetermined minimum rate and to uncouple the pans to render the auxiliary pan independent of the operation of the first pan when the train speed falls below such predetermined rate.

In witness whereof I have hereunto signed my name in the presence of two subscribing witnesses.

JOHN TAYLOR.
